Patented Sept. 7, 1926.

UNITED STATES PATENT OFFICE.

BAGSTER ROADS SEABROOK, OF MISHAWAKA, INDIANA.

SOUND-BOX ATTACHMENT FOR RECORDING HORNS.

Application filed May 3, 1922. Serial No. 558,048.

My invention relates to improvements in sound box attachment for recording horns and it consists more especially of the features pointed out in the annexed claims.

5 The purpose of my invention is to provide means for recording sounds which are received by and are delivered from a recording horn; that will enable me to record such sounds more faithfully than has heretofore been possible; that provides an annular opening around the horn outlet so as to form a communication between the exterior and interior of the connection between the sound box and the horn before the sound 10 waves reach the translating diaphragm; that provides a non-metallic portion in the connecting tube leading from the horn to the sound box; and that by reason of the related parts enables me to record spoken, 15 musical or other sound waves upon a suitable master surface in their original purity without making interfering additions thereto or absorbing required values therefrom.

20 With these and other ends in view, I illustrate in the accompanying drawing such instances of adaptation as will disclose the broad underlying features without limiting myself to the specific details shown thereon or described herein.

25 Figure 1 is an elevation in section of the several parts, the large end of the horn being shown in broken relation.

Fig. 2 is an elevation in section of a modified form of horn end.

30 Fig. 3 is an elevation in section on line 3—3 of Fig. 2.

Fig. 4 is a diagrammatic elevation of a horn in approximate recording relation.

35 Fig. 5 is a diagrammatic plan view of Fig. 4.

Fig. 6 is a plan view of a multi-connection sound box.

40 In practically carrying out my invention, I use a recording horn formed of a paper-like support, such as mill board etc., on which is placed a plastic self-setting non-absorptive and non-responsive composition that is of the required thickness at the large 45 end and gradually reduces in thickness toward the small end, thus preventing the horn from setting up sympathetic vibrations and on account of the compactness of the composition preventing sound waves being absorbed by the same thereby faithfully delivering the sound waves from the

horn without having had additions made thereto or subtractions taken therefrom.

45 For recording purposes, horns of the type described in my Patent No. 1,358,883 of Nov. 16, 1920 are preferred, or their substantial equivalent, in which the wall at the large end is thickest, gradually reducing in thickness toward the small end. Such horns have an outer wall of plastic self-setting cement-like composition 1 which is placed over a paper-like interior 2. At the small end this is formed around a conical tube or delivery member 3 that is integrally 50 connected to a supporting flange 4 and this flange has a tubular extension 5 which terminates in an exteriorly formed cone 6.

55 The flange 4 in the form shown in Fig. 1 has radial ears 7 corresponding to bosses 8 formed on the flange or sound responsive connection 9 of the extension or tubular projection 10. Screws 11 hold the parts 4 and 9 in assembled relation. The tube 10 has a conical portion 12 which joins onto the uniform diameter 13 of the tube 10, near the outer end of the tube 5. Between the conical end 12 of the tube 10 and the conical exterior 6 of the tube 5 an annular passage 14 is formed. This insures a spaced apart 60 relation between cones 6 and 12 which separates the parts so as to have a layer of air 65 between them.

70 The tube 10 is further reduced in diameter by means of the conical ends 15. There is slipped over the end 15, a rubber tube 23 which has a shoulder 24 that abuts the conical end 15. This rubber tube 23 extends onto the straight portion of the tube 10 and at this point is surrounded by a holding band 26. The other end of the tube 23 75 has a recess 25 which abuts the conical tube 17 of the sound box 16, and a holding band 27 is placed around the small end of the tube 23. The internal arrangement of these 80 parts is such that the diameter is gradually reduced from the straight portion of the tube 10 to the sound box 16. In assembling the parts, the bands 26 and 27 are slipped over the ends of the rubber tubes 23 and then the sound box and the tube 10 are 85 inserted in their respective places. The sound box 16 may be of any desired type, but I have exemplified a form that is made the subject of a separate application in which a curved diaphragm 18 is placed between suitable gaskets and the inner face of the sound 90 box is lined with a non-responsive and non- 95

100

105

110

absorbent composition 22 similar to the horn body 1. The diaphragm 18 is connected to stylus bar 19 which is pivoted at 20, the outer end having recording stylus 21 attached thereto.

In case it is found desirable to protect the annular opening 14 from side drafts indicated by the arrows in Fig. 1, a protecting flange 37 shown in Fig. 2 forms a horizontal annular passage 38 which, if desired, will prevent such side drafts. This flange is connected to the radial flange 35 that is a substitute for flange 4 shown in Fig. 1. A recess 36 may be formed in flange 35 against which the outer edge 39 of the feet 8 projecting from the flange 9 may have bearing so as to hold the conical portions 6 and 12 in concentric relation.

The horn 1 may be suspended at the large end from ears 29 by means of suspension wires 31, which ears being placed some distance apart to prevent the horn rocking on its axis. The small end may be suspended from eyes 28 secured to the flange 4 or 35 as shown in Fig. 3 by means of a suitable suspension 30. The sound box including the suspended horn may be moved mechanically so that the recording stylus will follow a spiral path on the recording disk by any desired expedient. In Fig. 5, I have diagrammatically instanced a bell crank lever 32 pivoted at 33 and having one leg pivoted to the holding ring 27 and the other leg

connected to any desired mechanical movement that is coordinated with the speed of 35 rotation of the recording disk 40.

This invention is claimed in its broadest scope to include a recording or transmitting horn having a heavy wall at the receiving end and a gradually reducing thickness 40 thereof toward the other end, such horn co-operating with means for recording sound waves that have been projected into the horn and admitting air between the horn and the sound-responsive device attached thereto. 45

What I claim is:—

1. A sound directing horn, a delivery member for the small end of the horn, a tubular extension therefrom, a support for a sound responsive connection, a projection 50 therefrom having an opening of greater diameter than the tubular extension, and means for holding the parts in concentric spaced-apart relation to each other.

2. In sound directing horns, a terminal 55 member for the small end of a horn, comprising a projection to which the horn is secured and a tubular sound delivery extension communicating with the interior of the horn, and an exteriorly positioned sound 60 receiving and translating member suitably supported in spaced-apart relation to the latter tube.

In testimony whereof I affix my signature.

BAGSTER ROADS SEABROOK.
